UNITED STATES PATENT OFFICE.

FRANK J. FERRELL, OF NEW YORK, N. Y.

DESIGN FOR A HAND-WHEEL.

SPECIFICATION forming part of Design No. 20,056, dated July 29, 1890.

Application filed July 1, 1890. Serial No. 357,423. Term of patent 14 years.

To all whom it may concern:

Be it known that I, FRANK J. FERRELL, a citizen of the United States, and a resident of New York, county and State of New York, have invented a certain new and original Design for Hand-Wheels, of which the following is a specification, reference being had to the accompanying drawings, which form part hereof.

10 The invention relates to a design to be worked upon or shape to be imparted to hand-wheels or other similar wheels; and it consists of the novel configuration and grouping herein shown and claimed.

15 In the accompanying drawings, Figure 1 is a front view of a hand-wheel showing my new design, and Fig. 2 is a back view of the same.

The frame of the wheel comprises an outer ring *a*, an inner hub *b*, and a series of spokes *c*, joining the ring and hub. Each face of the hub *b* contains an ornament, the main feature of which is a toothed circle. The spokes *c* each contain on each face an ornament com-

posed of converging and diverging curved lines.

25

The characteristic and essential feature of my design consists of the configuration representing a serpent entwined about the parts of the wheel. The tail of the serpent is entwined about and partly covers one of the 30 spokes *c*, and the figure of the serpent then passes over and around the outer ring *a* and entwines about the ring in many convolutions, encircling the ring so that the head of the serpent is close to the beginning of the 35 convolutions.

Having now described my invention, what I claim, and desire to secure by Letters Patent, is—

30 The design for hand-wheels, consisting of 40 the design substantially as shown.

FRANK J. FERRELL.
